UNITED STATES PATENT OFFICE.

VERNON ROYLE, OF PATERSON, NEW JERSEY.

CIRCULAR LOOM.

1,177,358.

Specification of Letters Patent. Patented Mar. 28, 1916.

Application filed December 19, 1914. Serial No. 878,163.

To all whom it may concern:

Be it known that I, VERNON ROYLE, a citizen of the United States, and resident of Paterson, in the county of Passaic and State 5 of New Jersey, have invented a new and useful Improvement in Circular Looms, of which the following is a specification.

My invention relates to circular looms and more particularly to the weaving pin support for use in connection with such looms.

The object is to provide a support capable of being vertically and laterally adjusted and fitted to receive weaving pins either tubular or solid and of varying diameters and 15 with these ends in view, my invention consists in certain features of construction and combinations of parts as will be hereinafter described and pointed out in the claims.

In the accompanying drawings, Figure 1 20 is a top plan view of a weaving pin and parts of the central column of a circular loom intimately associated therewith, Fig. 2 is a vertical section of the same in the plane of the line A—A, Fig. 1, Fig. 3 is a 25 detail elevation showing the rack and pinion for raising and lowering the weaving pin support and hence the weaving pin, Fig. 4 is an enlarged top plan detail showing the means for holding the pin support against 30 rotation and for securing the pin removably to its support, Fig. 5 is a transverse section in the plane of the line B—B, Fig. 2, showing the worm and worm wheel for operating the aforesaid raising and lowering 35 pinion, the worm shaft being shown in section with operating handle removed, and Fig. 6 is a vertical section in detail showing the means for securing a weaving pin of lesser diameter to the pin support.

40 The pin support is here shown as tubular and is denoted by 1. The weaving pin is also shown as tubular and is denoted by 2 in Figs. 1, 2 and 4, and by 2* in Fig. 6. The central hollow column of the loom in 45 which the weaving pin support 1 is located, is made up of a tubular step piece 3, and the superposed hubs and hub extensions of loom elements which form no part of my present invention except in so far as 50 they form a housing for the weaving pin support. The support 1, together with the weaving pin 2 carried thereby, is raised and lowered by means of a rack 4 on its side, in the present instance at its lower portion, 55 which rack is engaged by a pinion 5 on a shaft 6 journaled transversely in the base 7

of the central column and operated by a worm wheel secured on the shaft 6 engaged by a worm 8 on a shaft 9, the latter operated by any suitable and well known means, for 60 example, a crank, not shown. To hold the support 1 against a rotary motion, it is provided with laterally projecting lugs 10, 11, at its upper end, here shown as diametrically disposed and fitted to enter pockets 12, 65 13, in a ring piece 14 fixed in the central column of the loom.

The weaving pin 2 shown in Figs. 1, 2 and 4, has a diameter equal to that of the support 1 and is the largest size feasible to 70 use in my present structure. Its lower end fits within the upper end of the support 1 and a laterally projecting narrow flange 15, (see Fig. 4) rests on the inner portions of the upper ends of the lugs 10, 11. Screws 75 16, 17, are tapped into the upper ends of the lugs 10, 11, in such position that their heads overlap the flange 15 and lock the pin 2 to the support 1. To enable the pin to be removed without removing the screws, the 80 flange 15 is mutilated by providing it at intervals with recesses 18, (see Fig. 4) which, when the screws 16, 17, are loosened and the pin 2 rotated to bring a recess 18 into register with a screw head, permit the pin to be 85 lifted out and replaced at pleasure. To determine the point at which the weaving shall take place about the pin 2, a ring 19 is provided, the upper end of which embraces the pin with a sliding fit and forms a shoulder 90 20 in immediate proximity to the surface of the pin. The weaving point ring 19 is carried by a base ring 21 through the walls of which adjusting screws 22 pass and impinge against the outer wall of the ring 19. The base ring 21 is in turn seated in a fixed step 95 23 through bosses 24, 25, of which there are horizontal bores 26, 27, and counter bores 28, 29, in the latter of which screws 30, 31, with cone-shaped inner ends are engaged. The said cone-shaped inner ends coact with the inclined outer ends of plungers 32, 33, in the bores 26, 27, to adjust the base ring 21. The weaving point ring and the base 100 ring with their means of adjustment serve to center the weaving pin with respect to the vertical axis of the loom with great precision.

When it is desired to employ a weaving pin of less diameter than the maximum, I 110 employ what I am pleased to call an "adapter" for securing the weaving pin to

the pin support, and the weaving point ring is also modified to suit the diameter of the weaving pin. The latter, however, requires only the inward extension of the annular shoulder, as shown at 34, Fig. 6.

The adapter consists of a plate 35 with a central upwardly extending hub 36 in which the weaving pin 2* is secured in a manner quite similar to that in which the pin 2 is secured to its support as has been hereinabove explained, and a downwardly extending annular portion 37 provided with a narrow lateral flange corresponding to the flange 15 on the pin 2 and fitted to be secured in the upper end of the support 1 in the same manner as the pin 2, is fitted and secured.

While I have shown the weaving pins hollow or tubular, it is obvious that they might 20 be solid if so desired and secured to the support or adapter in the same manner as the tubular pins are secured. In practice one adapter may be used for several sizes 25 of weaving pins by simply making the bases of the weaving pins fit the adapter as herein shown.

It will be noted that the weaving pins may be removed and exchanged at pleasure through the top of the column and that 30 the pin support may also be lifted out by simply removing the weaving point ring and its base ring, and that the projection of the weaving pin upwardly through the weaving point ring may be made greater or 35 less to suit the desired retarding friction of the woven tube between the shoulder 20 and the end of the weaving pin.

It will also be noted that the "adapter" and weaving pin 2 are interchangeable in 40 the structure shown in Fig. 1, the assemblage of parts shown in Fig. 6 being introduced simply to show the modification of the weaving point ring when the "adapter" is used.

45 What I claim is:

1. In a circular loom, a weaving pin, a weaving point ring surrounding the weaving pin, a tubular support for the pin and means for adjusting the said support and hence the pin relatively to the ring.

2. In a circular loom, a weaving pin, a weaving point ring surrounding the pin, a

tubular support for the pin and gear in direct engagement with the support for adjusting the said support and hence the pin 55 relatively to the ring.

3. In a circular loom, a weaving pin, a weaving point ring surrounding the pin, a tubular support for the pin, the tubular support being provided with a rack on its outer 60 wall, and a pinion engaged with the rack for raising and lowering the support and hence the pin, relatively to the said ring to increase or diminish the retarding friction on the woven fabric.

4. In a circular loom, a tubular weaving pin support, a weaving pin provided with a mutilated flange and a screw carried by the support with its head in position to escape the mutilated portion of the flange 70 and overlap the non-mutilated portion of the flange for removably securing the pin to the support.

5. In a circular loom, a weaving pin provided with a mutilated flange, a weaving 75 pin support provided with laterally projecting lugs and screws engaged in the said lugs for removably securing the pin to the support.

6. In a circular loom, a weaving pin, a 80 weaving point ring and means for centering the pin and ring with respect to the vertical axis of the loom.

7. In a circular loom, a weaving pin, a tubular weaving pin support, means for 85 raising and lowering the support and hence the pin and means for adjusting the pin laterally to center it.

8. In a circular loom including a central hollow column, a weaving pin, a tubular 90 weaving pin support fitted to the interior of the column and means for adjusting the support within the column, the said pin and its support being removable from the loom through the top of said column.

In testimony, that I claim the foregoing as my invention, I have signed my name in presence of two witnesses, this 25th day of November, 1914.

VERNON ROYLE.
